UNITED STATES PATENT OFFICE

ERIK A. SODERBERG, OF ALAMEDA, CALIFORNIA, ASSIGNEE OF ONE-HALF TO GEORGE GUNDERSEN, OF ALAMEDA, CALIFORNIA

CAN HANDLING DEVICE

Application filed January 11, 1929, Serial No. 331,933. Renewed January 19, 1931.

This invention relates to improvements in can handling devices.

The principal object of this invention is to provide a device whereby a plurality of cans may be picked up, carried and deposited in a single operation in counter distinction to the customary method of grasping two or more cans in the hands transporting them and returning for more.

10 Another object is to produce a device wherein a row of cans as commonly found in the transporting boxes may be picked up as a line and redeposited at a distant point, still maintaining the cans in line.

15 A further object is to produce a device which is economical to manufacture and one which may be operated by an unskilled laborer.

20 A still further object is to provide automatic means for grasping the cans when the handles are moved toward each other.

Other objects and advantages will be apparent during the course of the following description.

25 In the accompanying drawings forming a part of this specification and in which like numerals are employed to designate like parts throughout the same,

Figure 1 is a side elevation of my device, 30 Figure 2 is a top plan view of Figure 1,

Figure 3 is an enlarged detailed cross section taken on the line 3—3 of Figure 2, and

35 Figure 4 is a diagonal view showing the manner in which the cans are deposited in the transporting boxes.

In canneries and the like places where a large number of cans are handled, in some instances the cans pass from the cookers into transporting boxes and are then transported to a distant point from which point they are lifted out of the boxes by hand and stacked in the storage space. In other instances the cans are carried by hand from the cooker to the storage space. In either case the operator can only grasp four cans, two in each hand at a time, with the result that a large number of men are required to do the stacking and as a consequence are

50 in each other's way a good part of the time.

With my device it is possible to pick up a large number of cans in a least possible time equal to that required to pick up one can transport them and deposit them with a minimum amount of effort.

55 My device consists essentially of two parallel strips 5 and 6 to the sides of which are secured corrugated plates 7 and 8 respectively. It will be noted in Figure 1 that the lower extremities of these plates are serrated which enables the same to enter between the cans more readily. These plates are secured in any convenient manner. Each plate has a series of openings 9 formed therein which openings permit the edge of the can to pass therethrough. L-shaped brackets are shown 60 at 11 and 12 and are secured to the strips 5 and 6 respectively. There is a set of these brackets near each end of the strips and by viewing Figure 2 it will be noted that diagonal slots 13 and 14 are formed in these brackets so that pins 16 and 17 respectively 65 carried upon the handles 18 will extend into the slots. These handles 18 are mounted upon pivot bolts 19 and carried in the upturned ends of the brackets 11 and 12. The result of this construction is that when the handles 18 are moved away from each other 70 at their upper ends the parallel strips 5 and 6 will be spread apart and the device as a whole may then be placed over a row of cans as shown in Figure 1. As soon as the strips 5 and 6 engage the tops of the cans the handles 18 are then moved toward each other and the pins 16 and 17 acting in the 75 slots 13 and 14 will cause the parallel strips to move toward each other with the result that the corrugated plates 7 and 8 will be brought into engagement with the cans to such an extent that the rolled edge of the can

80 A will extend through the slots 9 which will prevent the cans from dropping out from the bottom of the plates.

85 By now lifting the device as a whole, the cans may be lifted and deposited in any 90 place desired. When the handles are spread the cans will be released and the device is ready to pick up a further set of cans.

95 It will thus be seen that my device will accomplish all the objects above set forth.

It is to be understood that the form of my invention herewith shown and described is to be taken as a preferred example of the same and that various changes relative to the material, size, shape and arrangement of parts may be resorted to without departing from the spirit of the invention or the scope of the subjoined claims.

Having thus described my invention, I

10 claim:—

1. In a device of the character described, a pair of parallel strips, corrugated plates secured to said strips, said plates having openings formed therein for the purpose of 15 engaging the article to be carried, a pair of handles pivotally supported on said parallel strips and means carried by said handles for moving said strips toward and away from each other.
- 20 2. In a device of the character described, a pair of parallel strips, brackets secured to said strips at opposite ends thereof, a handle pivoted to said brackets, pins extending from each end entering cam slots formed 25 in said parallel strips, corrugated plates carried on said parallel strips and having openings formed in the vertical walls thereof for the purpose of engaging the edge of the article to be carried in the manner described.
- 30 3. In a device of the character described, a pair of horizontally disposed parallel strips, brackets secured to said strips at the opposite ends thereof, a handle pivoted to said brackets, pins extending therefrom and 35 entering cam slots formed in said parallel strips, corrugated plates depending from said parallel strips and having openings formed in the vertical walls thereof for the purpose of engaging an edge of the article to be carried in the manner described.
- 40 4. In a device of the character described, a pair of horizontally disposed parallel strips, brackets secured to said strips at the opposite ends thereof, a handle pivoted to 45 said brackets, pins extending therefrom and entering cam slots formed in said parallel strips, corrugated plates depending from said parallel strips and having openings formed in the vertical walls thereof for the 50 purpose of engaging an edge of the article to be carried, said vertically disposed corrugated plates having a serrated lower extremity.

In testimony whereof I affix my signature.
55 ERIK A. SODERBERG.
